Primary Examiner — Susan Moon Lee*(74) Attorney, Agent, or Firm* — Patterson & Sheridan, LLP**CLAIM**

I claim the ornamental design for a KVMP switch system, as shown and described.

DESCRIPTION

FIG. 1 is a front isometric view of a KVMP switch system; FIG. 2 is a back isometric view of the KVMP switch system of FIG. 1;

FIG. 3 is a back view of the KVMP switch system of FIG. 1; FIG. 4 is a top view of the KVMP switch system of FIG. 1; FIG. 5 is a front view of the KVMP switch system of FIG. 1; FIG. 6 is a bottom view of the KVMP switch system of FIG. 1;

FIG. 7 is a side view of the KVMP switch system of FIG. 1; and,

FIG. 8 is a side view of the KVMP switch system of FIG. 1. The KVMP system includes a housing having a circuit switch embedded therein. A plurality of computer ports, console ports, selector switches and a toggle switch are formed on the housing configured to control switch of computers coupled to the ports of the KVMP system to console devices.
